UNITED STATES PATENT OFFICE.

ROBERT C. RUSSELL, OF PITTSBURGH, PENNSYLVANIA.

CARD INDEX.

Application filed October 29, 1924. Serial No. 746,634.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in indexes and more particularly to those of the "visible" type,—one object of the present invention being to so construct the cards or index elements that they may be mounted in the holder or slide in such manner that they may be supported, one by another, in uniformly spaced relation to each other with the index data on said card or index element exposed to view; to so construct and arrange the index elements that they may be moved or removed but so that they will be held normally in place, and so that the index elements may be readily assembled without danger of annoying conflict with each other during the act of assembling.

A further object is to so construct and arrange the index elements that they will be properly guided to intermeshing relation with each other, and so that lateral displacement of the index elements relatively to each other shall be prevented.

With these and other objects in view, the invention consists in certain novel features as hereinafter set forth and pointed out in the claims.

In the accompanying drawings,—

Figure 1 is a face view illustrating a card index embodying my invention.

Figure 2 is a rear view in perspective of one of the cards or index elements.

Figure 3 is a similar view showing a plurality of index elements.

Figure 4 is a rear face view showing a plurality of index elements.

Figure 5 is a view in section on the line 5—5 of Figure 1, and

Figure 6 is a view illustrating a modification.

My improved index includes a plurality of holders for receiving the card or index elements and in the drawings, one such holder is illustrated at 1. The holder 1 may be made of metal in the form of a slide, drawer or

leaf and comprises a base member 2 having flanges at its respective ends forming shoulders 3—3 and also having flanges 4 at its longitudinal edge portions,—said flanges 4 overlying and spaced slightly from the base portion 2 of the holder so as to provide guideways 5 for the end portions of the index cards or elements 6.

Each index card or element 6 (which may be made of card or other suitable material) is notched as at 7 and the material bent rearwardly and upwardly to form tongues 8 at respective ends of the index element,—the points of juncture of these tongues with the body portion of the element being preferably curved slightly as indicated at 9. The tongues 8 have a tendency to spring away from the rear face of the card or element so that when the end portions of the latter are disposed on the guide-ways 5 of the holder 1, they will so engage the bottoms of said guide-ways as to cause the index element to be frictionally held against displacement. In cutting the spring tongues 8 from the material of the card, their inner portions are beveled and tapering, laterally projecting tongues 10 will be provided. These tongues 10 terminate inwardly from the ends of the card and the points of juncture between the inner ends of the tongues 8 and 10 will be slightly curved as indicated at 11. The material of the card extends downwardly below the tongues 10 as indicated at 12 and the respective ends of this portion 12 are beveled or inclined as shown at 13. In order to facilitate the ready assembling of the cards or elements within the holder 1, they will preferably be beveled at their respective ends as indicated at 14 or they may be rounded as shown at 15, Figure 6.

In assembling the cards or index elements, the laterally projecting tongues 10 (which will preferably be rounded or beveled at their free ends) on one card or element will become seated in the pockets formed by the upturned spring tongues 8 and the depending portion 12 of one card will become disposed between the inner ends of the tongues 8 of an adjacent card. The beveling of respective ends of the portion 12 will facilitate the guiding of one card into intermeshing relation with an adjacent card and the shoulders 13 will provide stops or abutments at the outer ends to engage the inner ends of tongues 8 on such adjacent cards.

and thus lateral displacement of one card with relation to another will be prevented. If desired however, the portion 12 of the card may be omitted, as illustrated in Figure 6.

With my improvements, the definite and uniform spacing of the cards with relation to each other so that the exposed portions of the cards on which the index data is inscribed will be uniform throughout the series of cards. While the cards or index elements will be held normally in proper positions and relations to each other, any card or element may be readily removed and easily replaced by a new card or element.

Having fully described my invention what I claim as new and desire to secure by Letters-Patent, is:

1. In a card index, an index element provided with a plurality of rearwardly and upwardly projecting members forming pockets and with tongues below such pockets to enter the pockets in a like element.

2. In a card index, the combination with a holder, of a plurality of index elements removably mounted in said holder, each of said index elements having upwardly projecting members forming pockets adjacent its rear face and each of said index elements having tongues adjacent to and under said pockets and adapted to enter the pockets of an adjacent index element, whereby each index element will be supported by another

with the exposed portions of all the index elements of uniform dimensions.

3. A visible index, comprising a holder having parallel guide-ways at its edge portions and a plurality of index elements each having upturned tongues at its ends to enter said guide-ways with the end portions of the element and frictionally hold the element in place and each index element also having tongues below said upturned tongues and adapted to be supported in pockets formed by the upturned tongues of another index element.

4. In a visible index, the combination with a holder having parallel guide-ways, of a plurality of index elements adapted at their ends to enter said guide-ways, each index element having pockets beyond respective sides of its center and also having tongues to enter pockets of an adjacent element and each index element having a depending portion forming beveled shoulders at the inner ends of said tongues and adapted to enter between the inner ends of the pockets of an adjacent index element.

In testimony whereof, I have signed this specification in the presence of two subscribing witnesses.

ROBERT C. RUSSELL.
